legs 71. Legs 71 are affixed to a bent axle 70, and the other end has a roller 73. A spring 74 exerts pressure on the leg channel 71. This pressure keeps the channel 71 pushed back past stop pin 72. In the up position, the bent arm or axle 70 lies to the back of the tab on bracket 53. Pin 75 is a stop for the leg in down position.

The FIGURES 9 and 10 show the detent cut out 59 in runner angle 52 and the rear roller 32 resting in the detent 59. The roller bracket 31 supports the roller by means of an axle rivet 37.

FIGURE 14 is a view of the cable layout and the relative motion of each element therein. The rollers 54 mounted on horizontal axles are for redirecting the cable 80. The upper rollers 57 and lower rollers 58 are mounted on substantially vertical axles. The cable 80 is crossed by having the cable go from roller 58 to roller 57 and vice versa. As is illustrated cable 80 may be made of one piece and joined by means of a cable connector 82, thus forming an endless cable means. On the rear of frame 30 are clip holes 34 which are adapted to accept clips 81. When thus used, the cable 80 will have an equal movement in every element. Thus one of the attached clips 81 being moved to or away from roller 54 will have an equal and corresponding movement on the other clip 81, in this manner parallel movement of the frame 20 is maintained.

Construction

As shown in FIGURE 4, my invention is designed to furnish a sloped seat and a level sleeping surface. Further the unit is a combination of elements whereby the furniture frame is strengthened and reinforced by the use of my unit. By utilizing the strengthening feature and providing a lateral support the lower support unit 50 permits the use of a furniture frame 60 with or without a front piece.

As the unit is constructed to permit the design of a sloped seat so also are the locking devices. To prevent any rolling of the upper frame while being used as a sitting means, the detent retains the rear roller and thus restricts the upper frame from tending to roll up the slope particularly when a person leans against the back causing a forward motion on the seat. To prevent any considerable thrust to cause the upper frame to roll out of the detent, which is a minor retardment, the leg locks prevent the unwanted opening of the unit. The double lock thus afforded prevents children or others from accidental opening. A further intent is to make sure that both legs are in a proper down position for rolling before the unit is able to be rolled outward.

Ease of operation is provided by the rollers 31 at the rear of the upper frame 30 and the grooved rollers 54 at the front of the bottom support unit 50. The upper frame 30 is kept in alignment by the two grooved rollers 54 and the affixed cable 80 as assembled, and as illustrated in FIGURE 14. The upper cables 80 operate in the same direction, thus by having a taut cable assembly and the upper frame 30 affixed at the rear point 34, to the cables 80, permits the upper frame 30 to roll in and out and still maintain alignment. This condition persists, no matter where the upper frame is grasped in order to open or close.

Operation

As shown in the figures, in a seat construction either sofa or upholstered chair, the upper frame 30 is pushed in so as to permit the rear wheels 32 to rest in detent 59. In addition, the unit is locked against unintended or accidental opening by means of the bent rod 70 which engages bracket tab 53, when the legs 71 are in the up position. Further in the closed condition the cushion part 66B rests upon cushion part 66A. Whether hinged by a cloth tab or separate, the double thickness of the cushion 66 gives a most comfortable seating medium.

To open and prepare as a sleeping accommodation the

following procedure and mechanical functions are performed. The operator reaches under the front of the facing 67 and lowers legs 71 by pulling forward and compressing spring 74 sufficiently to bring leg 71 forward of stop pin 72, thus enabling the leg to be rotated 90° or more downward. The downward motion is such as to cause the leg 71 to go slightly past the vertical and come to rest against stop pin 75. Since the unit is on a slope the rollers 73 do not touch the floor. The unit can now be pulled forward. Grasping the front 67 if such is a part of the design or any front part of upper frame 30 a small jerk will cause the rear rollers 32 to move out of the detent 59, then continuing the pull the grooved rollers 54 and rear rollers 32 will permit easy rolling motion and upper frame 30 will continue to move up and forward until the unit reaches a balance point over grooved rollers 54. At this point the upper frame 30 will drop the wheels 73 of the legs 71 to the floor and the forward progress will continue on these four rolling members. Before the forward motion is complete the cable loops 44 engage the cable clips 35 causing the swing frame 40 to move forward. The links 41 and 42 cause the frame 40 to lift the rear part more than the front. The upper frame 30 having traveled the maximum forward distance as limited by roller 32 coming up to grooved roller 54, the swing frame 40 will come to rest against upper frame 30 and the links 42 and 41 are rotated past the vertical effecting a gravitational lock. The swing frame 40 is assisted in its lift by means of the springs 55 which in effect make the swing frame nearly weightless and permit as nearly an effortless operation as practical. The cable assemblies 80 assures the constant alignment of the upper frame 30 and the grooved pulleys 54 limit the side play of the upper frame 30. After the completion of the opening of the unit cushion 66B is either turned or placed on the springs unit 68 or a board section support in place of the springs. In this manner the sleeping unit is converted from the seating unit. To convert to a seating unit the opening procedure is reversed.

It is thus shown that a convertible article of furniture is economically provided for home or office whereby both seating and sleeping facilities are easily provided with a minimal amount of inconvenience and effort.

The above disclosure is by way of illustration and while a specific embodiment has been shown and described it will of course be understood that various other modifications may be devised by those skilled in the art which will embody the principles of the invention and found in the true spirit and scope thereof.

What is claimed is:

1. A convertible seating mechanism comprising in combination:
  - a. a bottom framework structure and a first roller support attached thereto,
  - b. a swing frame which is link connected to the bottom framework and adapted to rest thereon,
  - c. an upper framework with a second roller means attached thereto, said upper framework being supported on the first roller support means and second roller means, whereby the upper framework is moveable laterally out and in,
  - d. a tie brace attached to the upper framework, and having cable engaging clips attached thereto,
  - e. a cable loop means attached to the swing frame and engaging and slideable on the tie brace so that as the upper framework is moved outward the cable loop means slides on the tie brace until engaging the cable engaging clips whence the swing frame is moved forward and upward on links,
  - f. a parallel cable assembly comprising a cable formed into an endless cable, the cable co-acting in roller guides affixed to the bottom framework structure, the cable also being attached to each end of the upper framework whereby as the upper framework is moved out and in, the parallel cable causes an equal

movement in both ends of the upper framework.
 2. Structure according to claim 1 wherein a spring means is attached to the bottom framework structure, said spring means adapted to urge the swing frame into a predisposed position above the bottom framework.

3. Structure according to claim 2 wherein the upper framework has a manual operated leg support, said leg support comprising a channel member one end of which has a roller the other end having an axle attached, the axle being at right angles to the channel member, the axle member further having one end bent at an angle, the axle being retained by a bracket bearing support, the bent end of the axle adapted to engage a bracket affixed to the bottom framework structure when the leg support is turned to a position parallel to the upper framework, and further that the channel member of said leg support engages a stop pin to prevent the accidental turning of the leg support.

4. Structure according to claim 3 wherein shallow de-

tents are formed in the bottom framework, the detents so arranged as to engage and receive the second roller means of the upper framework when the unit is used in a closed seating position, whereby the weight of the persons sitting on the structure will tend to hold the second roller means in the detents preventing unwanted movement of the upper framework.
